JEWELRY ARTICLE

Everett H. Lundsten, Attleboro, Mass., assignor to
 J. & L. Tool Company, Attleboro, Mass., a
 firm composed of Emil L. Johnson and Olof
 Lundsten, both of Attleboro, Mass.

Application December 28, 1935, Serial No. 56,506

6 Claims. (Cl. 63—20)

This invention relates to jewelry findings, more particularly to an article designed to mount a device such as a butterfly or the like, which can be attached to a dress as an ornament; and has 5 for one of its objects the provision of a simplified and inexpensive means of providing an attaching pin and yet such a means as will be strong and durable and better adapted to withstand the strains to which it is subjected.

10 Another object of the invention is the provision of an article provided with a pin which does not need to be soldered in position but is rather formed of a single integral piece from the stock of one of the movable sections of the article, 15 whereby the detrimental effects of soldering and skilled labor for a soldering operation may be dispensed with.

Another object of the invention is the formation of the pin for attaching the article in position at the same time that the stock for the end section is cut from the blank, the pin being shaped up from the sheet stock rather than separately formed.

Another object of the invention is the provision 25 of an article with pin points which will be of neater appearance than where solder has to be used or where the pins are attached by passing them through an opening in the section.

With these and other objects in view, the invention consists of certain novel features of construction, as will be more fully described, and particularly pointed out in the appended claims.

In the accompanying drawing:

Fig. 1 is a top plan view of the completed ornament utilizing my new jewelry finding;

Fig. 2 is a bottom plan view of the structure shown in Figure 1;

Fig. 3 is a side elevation showing the wings of the butterfly illustrated in the ornament of Figure 1 as swung about their hinge connection to the body;

Fig. 4 is a top plan view of the finding alone before the ornamental portions are mounted thereon;

Fig. 5 is a bottom plan view of the structure shown in Figure 4;

Fig. 6 is a side elevation of the structure shown in Figure 4 or 5;

Fig. 7 is a perspective view of the central section or middle section of the article;

Fig. 8 is a perspective view of one of the end sections of the article;

Fig. 9 is a perspective view of the blank from which the end section of Figure 8 is formed, the same being shown as blanked out before bending.

In the use of findings, such as articles having different sections hinged together, attaching means are usually clumsily secured thereto such as by soldering them in place or by passing them through openings in the sections for holding them in position, which present an unsightly appearance and an insecure structure and one requiring skilled labor for attachment, and in cases where soldered, the heat used causes an undesirable loss of the temper of the attachment; and in order to obviate these difficulties and undesirable effects, I have provided pins integral with the end sections which are bent into position with a saving in labor and skill and also providing a better construction; and the following is a more detailed description of the present embodiment of this invention, illustrating the preferred means by which these advantageous results may be accomplished:

With reference to the drawing, 10 designates 20 the middle or intermediate section which is provided with fingers which are rolled to provide ears 11 at one side and at 12 at the other side, as shown clearly in perspective in Figure 7. Each of the end sections 13 is cut from sheet stock in 25 the shape shown in Figure 9, with pins 14 extending to one side thereof and fingers 15 extending from the other side thereof, which fingers are rolled to provide ears 16, as shown in Figure 8. These ears 16 may be located in line with the 30 ears 11 and positioned between them for the reception of a pintle pin 17 for hinging these end sections to the body section 10.

The pins 14 of these end sections are bent as at 35 18 and again as at 19 forming a generally U-shaped structure so that the pins 14 extend back over the end section 13 and are spaced therefrom, as shown in Figure 6. At the time of assembly 40 of the end section with the middle section 10, springs 19 are positioned about the pintle pin 17 with their ends 20 and 21 positioned along the 45 surfaces of the sections 10 and 13 and lodged in the recess 22 in the section 10 and in the recess 23 in the section 13 so that the pressure of the spring tends to swing one end section about its pivot 17 in the direction of the arrow 24, shown in Figure 6; while the other spring tends to swing the other end section 13 about the pivot 17 in the direction of the arrow 25, shown in Figure 6, so that the pins 14 on the opposite end section will 50 be moved toward each other.

The movement of the end sections with the pins 14 toward each other, is limited, however, by the shape or formation of the sheet stock 10 and the section 13. For instance, as shown in 55

Figure 7, there is an abutment 26 formed by the stock adjacent each of the ears extending inwardly into the cut-out portion 27 of this body section; while the stock at 28 of each end section 13 extends outwardly beyond the ears and is in such a position as to swing against the edge of the stock 26 so as to limit the movement of the sections toward each other beyond the point shown in Figure 6. Thus, the movement of the section by the spring is limited by this stop when the sections will normally lie in a single plane, as shown in Figure 6, and the pin points will not actually contact or cross one another.

In use, an ornament conforming generally to the body portion of a butterfly as at 30 will be secured to the middle section 10 and ornaments conforming generally to the wings of a butterfly as at 31 and 32 will be secured to the opposite end sections 13.

To attach the butterfly to a dress, it is merely necessary to swing its wings into position, as shown in Figure 3, position it adjacent the surface of the fabric to which it is desired it will engage and release the wings, permitting the pins to swing toward each other into substantially the position shown in Figure 6, which will cause the fabric to be gripped between the ends of the pins or the pins to pierce the fabric to securely hold the ornament in position, the stops forming a limit so that the butterfly ornament is in substantially a single plane presenting a maximum of ornamental surface for display purposes.

The foregoing description is directed solely towards the construction illustrated, but I desire it to be understood that I reserve the privilege of resorting to all the mechanical changes to which the device is susceptible, the invention being defined and limited only by the terms of the appended claims.

I claim:

1. An article for jewelry use comprising a middle section and end sections hinged at either side thereof, springs at said hinges for swinging the end sections toward each other, said end sections being each provided with pins formed out of the same integral piece of material as said end sections and extending from the outer edge thereof distant from said hinged edge and doubled back on the section to extend over the back surface thereof and in spaced relation to the end section, said pins on said end section extending and being urged toward each other by said springs.

2. An article for jewelry use, comprising a middle section and end sections hinged at either side thereof, said end sections being each provided with pins formed out of the same integral piece of material as said end sections and extending from the outer edge thereof and formations at said hinge connection of the sections to limit the swing of said sections relative to each other so that the sections may lie in substantially a single plane.

3. An article for jewelry use comprising a middle section and end sections hinged at either side thereof, springs at said hinges for swinging the end sections toward each other, said end sections being each provided with pins formed out of the same integral piece of material as said end sections and extending from the outer edge thereof, and formations at said hinge connection of the sections to limit the swing of said sections relative to each other in one direction, said limit being such that the sections will be in substantially a single plane when the stops are in engagement.

4. A component of an article for jewelry use comprising a section of sheet metal having ears on one edge thereof and integral pins extending from another edge thereof doubled back on said section and in spaced relation to said section, and in spaced relation to each other throughout their angular extent.

5. An article for jewelry use comprising a middle section having ears on either side thereof, end sections having ears thereon, a pintle pin journaled through said ears for hinging these end sections to said middle section one on each side thereof, and formations on said ears positioned to engage each other to limit the swing of said sections relative to each other, said end sections each having pins extending from the outer edge thereof.

6. An article for jewelry use comprising a middle section having ears on either side thereof, end sections having ears thereon, a pintle pin journaled through said ears for hinging these end sections to said middle section one on each side thereof, each of said ears having an abutment thereon and positioned so that the abutments on each adjacent ear will register to engage each other to limit the swing of said sections relative to each other, said end sections each having pins extending from the outer edge thereof.

EVERETT H. LUNDSTEN.
